(57) **CLAIM**

The ornamental design for a bobber-shaped cooler, as shown and described.

DESCRIPTION

FIG. 1 is a front elevational view of the bobber-shaped cooler of the present invention;
FIG. 2 is a side elevational view thereof;
FIG. 3 is top plan view thereof;
FIG. 4 is an inverse side elevational view thereof;
FIG. 5 is a rear elevational view thereof; and,
FIG. 6 is bottom plan view thereof.
